ABRAHAM GOLDSTEIN AND BARNETT GOLDSTEIN, OF PATTON,
PENNSYLVANIA.

ENVELOP MOISTENING AND SEALING DEVICE.

SPECIFICATION forming part of Letters Patent No. 734,850, dated July 28, 1903.

Application filed May 27, 1903. Serial No. 158,933. (No model.)

To all whom it may concern:

Be it known that we, ABRAHAM GOLDSTEIN and BARNETT GOLDSTEIN, citizens of the United States, and residents of Patton, in the county of Cambria and State of Pennsylvania, have invented new and useful Improvements in Envelop Moistening and Sealing Devices, of which the following is a full, clear, and exact description.

10 The purpose of the invention is to provide a simple, durable, and economic device especially adapted for moistening the gummed portion of the sealing-flap of an envelop and for effecting a closure of such moistened flap 15 upon the body of the envelop, and, further, to provide a hollow cylindrical body or roller for such purpose adapted to contain liquid and one or more absorbent pads exposed at the exterior of the roller, which pads are held 20 in communication with the liquid contents of the roller.

A further purpose of the invention is to provide a handled pivoted bail for the roller and springs at the pivotal ends of the bail, 25 which springs are alternately placed under tension as the roller is operated in one or the other direction, whereby after operation in moistening or sealing the roller is restored to its normal position, since the roller is raised 30 after each of such operations.

The invention consists in the novel construction and combination of the several parts, as will be hereinafter fully set forth, and pointed out in the claims.

35 Reference is to be had to the accompanying drawings, forming a part of this specification, in which similar characters of reference indicate corresponding parts in all the figures.

Figure 1 is a perspective view of the device, 40 illustrating its application to the envelop to moisten the mucilaged surface of the sealing-flap. Fig. 2 is a sectional end view of the device. Fig. 3 is an end view of the roller, showing it operated in two positions—first, to moisten the sealing-flap, and, second, to close 45 the moistened flap upon the body of the envelop. Fig. 4 is an enlarged longitudinal sectional view through the device; and Fig. 5 is an end view of the device, illustrating it 50 in position to effect a closure of the moistened flap.

A represents the body of the device, which is in cylindrical or roller form and may be made of any suitable material—tin or sheet metal of any description, including aluminum—and the roller is provided with heads 55 10, properly secured therein. In one head an aperture is made, normally closed by a plug or cap 11, through which aperture liquid, preferably water, is supplied to the interior 60 of the roller.

The roller is provided between its ends with two pairs B and B' of slots 12 and 13. These slots are curved more or less and are concentric, and the slots of each pair are 65 more or less spirally placed, extending from the end portions of the roller to the central portion thereof, stopping at each side of a central bridge-section 14. The pairs B and B' of slots 12 and 13 are so arranged relatively to each other that combinedly they have an arched formation, as is illustrated in Fig. 1. The slots 12 and 13 of each pair B and B' are at suitable distances apart, as 70 is best shown in Fig. 2.

75 Preferably while the body portion of the roller A is in its flat state, at which time the slots 12 and 13 are produced therein, pads 15 of absorbent material are located at the back of the body of the roller, so as to occupy principally an inner position within the complete roller, as is shown in Fig. 4. These absorbent pads 15 are passed outward, for example, through the upper slots 12 and are returned inwardly through the lower slots 13, thus 80 causing sections of the said pads to be exposed at the bridge portions of the roller A between the slots 12 and 13, as is shown in Figs. 1 and 2. The pads 15 are held in position by means of rods or wires 16, which follow the 85 lines of the slots 12 and 13, as is shown in Fig. 4, and are attached by solder 17 or equivalent material to the inner face of the bridge portion 14 between the pairs B and B' of slots, and also by solder 18 or equivalent means, to 90 the inner face of the body A of the roller at points near the ends of said roller, as is shown also in Fig. 4.

A bail 19 is employed the ends whereof are bent at 20 horizontally and terminate in eyes 100 20^a, which loosely receive trunnions 20^b, centrally secured to the edges of the roller; and

the said bail 19, centrally between its ends, is provided with a handle 21, attached thereto in any suitable or approved manner. Finally, 5 springs 22 are coiled around the trunnions or pivotal sections 20^b of the cylinder-heads, and the ends of the springs 22 are made to bear against pins 22^a and 22^b, secured to the heads of the roller, while the other end of each spring is properly attached to a side member of the 10 bail 19, as is indicated in Figs. 1, 2, and 4. The springs bear against opposite sides of the pins 22^a and 22^b, the bearings being such that when the roller A is moved forward the right-hand spring is placed under tension and when 15 the roller is moved backward the left-hand spring is wound up.

The envelop C is laid upon a suitable support back upward and with the sealing-flap C' in more or less of a vertical position to expose 20 the gummed surface c, as is shown in Fig. 5. The cylinder or roller A having been supplied with a suitable quantity of liquid, the pads 15 become moistened and remain moistened as long as liquid is contained in 25 said roller. The roller is then placed on the body of the envelop, as is shown in Fig. 1, with the exposed portions of the pads 16 more or less uppermost, as is shown in the same figure, whereupon the roller is pushed forward 30 by means of the handle 21 until the exposed portions of the moistened pads 15 are brought in engagement with the mucilaged portion c of the flap of the envelop with the formation of which mucilaged border of the 35 sealing-flap the combined contour of the exposed portions of the moistening-pads more or less correspond. When the roller is free from the flap of the envelop, the flap resumes its upper position. (Shown in Fig. 5.)

40 As the cylinder A is rolled forward to moisten the mucilaged portion of the sealing-flap C', the right-hand spring 22 is placed under tension, and after the moistening operation is completed the device is lifted up from the 45 envelop, or a support upon which it is placed, and the said spring, unwinding, restores the cylinder or roller A to its normal position. Next, as is shown in Fig. 5 and in dotted lines in Fig. 3, the roller is drawn rearwardly over 50 the moistened flap and the body of the envelop, causing the moistened sealing-flap C' to uniformly adhere to the body of the envelop, and as the roller is carried in a rearward direction or toward the operator the 55 left-hand spring 22 is placed under tension; but the moment that the roller is again lifted from the envelop or the support upon which it is laid the roller is restored to its normal position, so that it is immediately in condition 60 to be passed over a second envelop to moisten the gummed surface of its sealing-flap.

Having thus described our invention, we claim as new and desire to secure by Letters Patent—

1. A device for moistening and sealing envelops, consisting of a tension-controlled roller having an interior chamber for the reception of a liquid, and absorbent pads located partially within and partially without the said roller, the exposed portions of the absorbent pads appearing at the peripheral surface of the roller, as described. 65

2. A device for moistening envelops, consisting of roller having an interior chamber 75 for the reception of a liquid, and absorbent pads located partially within and partially without the said roller, the exposed portions of the absorbent pads appearing at the peripheral surface of the roller, a bail for the roller, 80 and springs connected with the bail and roller, having tensile action in opposite directions, as set forth. 85

3. A device for moistening and sealing envelops, consisting of a roller, means for turning the said roller upon a support, the roller being provided with an interior chamber adapted to receive a liquid, and with exterior peripheral slots arranged in pairs, the inner ends of the slots of one pair approaching the 90 corresponding ends of the slots of the opposing pair, and absorbent pads held within the said roller, portions of which pads are carried upward through one slot of a pair and returned inward through the fellow slot of a 95 pair, as and for the purpose described. 95

4. A device for moistening and sealing envelops, or for similar purposes, consisting of a hollow roller having means at its ends for the introduction of a liquid, a spring-controlled bail for the said roller, the roller being provided with peripheral slots arranged in pairs, the slots of each pair having more or less of a spiral formation, the inner ends of the slots of one pair approaching the corresponding ends of the slots of the opposing pair yet being separated therefrom, the two pairs of combined slots representing substantially an arch, pads of absorbent material located mainly within the said roller, which pads are passed out from the roller through one slot of each pair and are returned within the roller through the mating slot of the same pair, and retaining devices for the pads, secured within the said roller, all operating for 110 the purposes set forth. 115

In testimony whereof we have signed our names to this specification in the presence of two subscribing witnesses.
